UNITED STATES PATENT OFFICE.

JEREMIAH J. O'CONNOR AND JOHN A. O'CONNOR, OF PAWTUCKET, ASSIGNS OF ONE-THIRD TO ALBERT H. ALLEN, OF PROVIDENCE, RHODE ISLAND.

MACHINE FOR TWISTING THREAD.

SPECIFICATION forming part of Letters Patent No. 372,700, dated November 3, 1887.

Application filed February 12, 1887. Serial No. 228,066. (No model.)

To all whom it may concern:

Be it known that we, JEREMIAH J. O'CONNOR and JOHN A. O'CONNOR, both of Pawtucket, in the county of Providence and State 5 of Rhode Island, have jointly invented a new and useful Improvement in Machines for Twisting Thread, &c.; and we do hereby declare the following specification, taken in connection with the accompanying drawings, forming a 10 part of the same, to be a description thereof.

This invention is an improvement upon that shown and described in Letters Patent of the United States, No. 354,926, issued to us December 28, 1886; and it consists in certain features 15 of construction and arrangement, whereby the mechanism for severing the thread is simplified and said mechanism is positively operated independent of the top rolls of the machine, as hereinafter described and claimed.

20 In the accompanying drawings, Figure 1 represents a front view of a portion of a thread-twisting machine embodying the invention. Fig. 2 shows a vertical section of the same on line *xx*. Fig. 3 represents a part of said sectional view on a larger scale. Fig. 4 shows in perspective the shear for severing the thread.

25 With the exception of the device for severing the thread and the mechanism for operating the same, the machine shown in the drawings is 30 an ordinary thread-twisting machine.

A is the frame.

B is the lower drawing-roll, which is driven from the drum *C* by a well-known train of gears, *c*, *c'*, *c''*, *c³*, and *c⁴*, (shown in full lines at 35 Fig. 1 and by dotted circles in Fig. 2,) the first gear of the train being secured to the drum and the last to the shaft *b* of the roll *B*.

D are the upper rolls—one for each thread—which are loosely mounted to revolve in bearings *d*, Fig. 1, by frictional contact with the roll *B*, or the threads passing between the rolls.

40 The threads *e* are delivered from spools or bobbins *E*, mounted on a creel or stand. Each of these threads, either singly or as one of a cable, passes first through a guide-eye, *f*, on the traverse-bar *F*, then through the device *G* for severing the thread, then, preferably, through another guide-eye, *h*, then around a rod, *j*, in the water-trough *J*, then over and partially 45 around the rolls *D B*. From the roll *B* the 50

thread passes over a guide-rod, *K*, thence to the receiving-bobbin *L*, through the usual traveler, which works on the ring *m*, mounted on the traverse-rail *M*. The bobbin *L* is mounted on the spindle *N*, which is driven by a band, 55 *n*, from the drum *C*.

The machine is supplied with as many severing devices *G* as there are threads running to the rolls *D B*. The device *G*, as particularly shown in Fig. 4, consists of two members, *g g'*, 60 the former of which is movable and the latter, preferably, rigidly secured to the side of the trough *J* or other support. The member *g* slides on or through the member *g'*, and said member *g* has an opening, *2*, through which the 65 thread passes on its way from the spools *E*, and is preferably provided with a side slot, *3*, which allows the thread to be quickly and easily inserted into said opening. For convenience, the member *g'* may be composed of two parts, *4 5*, 70 the latter of steel, preferably, having a sharp cutting-edge, *6*, at the top. The edge *7* of the member *g* may also be a cutting-edge, if desired. To the member *g* a bell-crank lever, *O*, is pivoted, the lower end, *o*, of which is hooked, 75 and the outer end, *o'*, of which is formed into an eye, or otherwise shaped so as to be supported by the thread, as shown in Figs. 2 and 3.

The member *g* of the device *G* may be held in the raised normal position (shown by full 80 lines in Figs. 2 and 3) by friction, as by fitting sufficiently tightly in the member *g'*; but a spring, *S*, is preferably employed for such purpose, which spring is secured to the member *g* and bears upon the member *g'*, as shown in 85 Fig. 4, with the requisite force to retain the member *g* at the proper elevation.

For operating the severing devices *G* the machine is provided with suitable means—such, for instance, as a shaft, *P*, furnished with 90 armed wheels *Q*—for engaging the bent ends *o* of the levers *O* when the threads break, so as to pull downwardly the members *g*, through which the broken threads run. As shown in Fig. 1, the shaft *P* extends longitudinally of the machine, and the armed wheels *Q* are secured to the shaft immediately behind the vertical arms of the levers *O*, respectively. The shaft *P* is driven by the short shaft *R*, to which the gear *e³* is secured, the said shafts being preferably 95 100

connected with each other by a clutch, S, the members of which can be disengaged, when desired, by a shipper, s, Fig. 2. Normally the hooked ends *o* of the levers *O* are held out of the path of movement of the armed wheels *Q* by the threads which support the outer ends, *o'*, of said lever. When a thread breaks between the rolls *B* *D* and the spindles, however, the end *o* of that lever *O* whose end *o'* was supported by such thread will swing toward the shaft *P*, as shown by dotted lines in Fig. 2, and be engaged by one of the arms *q* of that wheel *Q* which is placed immediately in the rear of said lever. The positive rotation of the wheel will draw downwardly the lever *O* and the shear member *g*, to which it is pivoted, and thereby cause the thread to be severed. The delivery from that spool whose thread has been cut will be stopped, therefore, and no thread will run to waste. In piecing up the ends the thread is passed through the eye *h*, under the rod *j*; over the rolls *D* *B*, thence through the eye *o'* of the lever *O*, then over the rod *K*, then through the traveler, and is tied to the end on the receiving bobbin. The member *g* of the severing device is then raised and the thread easily passed through the side slot, 3, into the opening 2.

What we claim, and desire to secure by Letters Patent, is—

1. The combination, with a thread-severing device, substantially as described, of a bell-crank lever pivoted directly to one member of said device and adapted to be held in a normal position by a passing thread, as described, and

means, substantially as described, for engaging said lever when the thread breaks, and thereby operating the severing device, substantially as set forth.

2. The combination, with a thread-severing device having a movable member, substantially as described, and means, substantially as described, for retaining said member in normal position, of a bell-crank lever pivoted directly to said movable member, and adapted, as described, to be held in normal position by a passing thread, and means, substantially as described, for engaging said lever when the thread breaks, and thereby operating the severing device, substantially as set forth. 50

3. The combination of the members *g* and *g'*, forming the thread-severing device *G*, the former member having an opening, 2, and side slot, 3, into said opening, substantially as set forth. 55

4. The thread-severer herein described, consisting of the members *g* *g'*, the former member having an opening, 2, and side slot, 3, the spring 8, for holding said members in position with relation to each other, and the bell-crank lever *O*, pivoted to the member *g*, the whole being adapted to be attached to a machine for twisting thread, &c., substantially as and for the purposes specified. 60
